DESIGN FOR A FACIAL MASK FOR USE IN ELECTROTHERAPY

Paul Meminger, Los Angeles, Calif.

Application December 1, 1944, Serial No. 116,649

Term of patent 14 years

(Cl. D83—1)

To all whom it may concern:

Be it known that I, Paul Meminger, a citizen of the Dominion of Canada, residing in the city of Los Angeles, in the county of Los Angeles and State of California, have invented a new, original, and ornamental Design for a Facial Mask for use in Electrotherapy, of which the following is a specification, reference being had to the accompanying drawing forming a part thereof.

Fig. 1 is a bottom plan view of a facial mask for use in electrotherapy showing my new design,

Fig. 2 is a front elevational view of said mask, and

Fig. 3 is a top view of the same.

I claim:

The ornamental design for a facial mask for use in electrotherapy, substantially as shown.

PAUL MEMINGER.
